BORING BAR

Filed Sept. 30, 1926 2 Sheets-Sheet 2

UNITED STATES PATENT OFFICE

FLOYD S. HARTWELL, OF CLEVELAND, OHIO

BORING BAR

Application filed September 30, 1926. Serial No. 138,741.

This invention relates to boring bars and is an improvement over the construction disclosed in United States Patent No. 1,342,447 dated June 8, 1920 and issued to William E. Kelly.

Briefly stated, an important object of this invention is to provide a boring bar in which the slot for the reception of the cutting element is of a cross sectional area to snugly receive the cutting element whereby the rear edge of the cutting element will have effective contact with the rear wall of the slot to relieve the cutter holding devices of thrust strains.

A further and equally important object of the invention is to provide a retaining and locking device for the cutting element having simple means whereby the same may be adjusted to properly position and hold the cutting element in place, this feature avoiding the necessity of employing taper locking screws as is now done.

Another aim of the invention is to provide a boring bar in which the arrangement and construction of parts is such that the manufacture and maintenance of the bar is greatly simplified and cheapened.

Other objects and advantages will be apparent during the course of the following description.

In the accompanying drawings forming a part of this application and in which like numerals are employed to designate like parts throughout the same,

Figure 1 is a fragmentary perspective of a boring bar constructed in accordance with this invention;

Figure 2 is a detail vertical sectional view through the boring bar;

Figure 3 is a horizontal sectional view taken on line 3-3 of Figure 2;

Figure 4 is a vertical transverse sectional view taken on line 4-4 of Figure 3;

Figure 5 is a vertical transverse sectional view taken on line 5-5 of Figure 2;

Figure 6 is a group perspective illustrating the locking and locating block and associated elements embodied in the invention;

Figure 7 is a group perspective illustrating a cutting unit embodied in the invention.

In the drawings, the numeral 5 designates a bar having conventional or other means by which the same may be attached to an operating mechanism. The forward portion of the bar has a slot 6 extending entirely therethrough for the reception of a cutting unit 7 of any preferred design. More specifically the cutting unit 7 may be in the nature of a block having separately adjustable blades adapted to extend out through opposite sides of the bar as in the case of other tools on the market. On the other hand, the cutting unit 7 may be in the nature of a single block, the ends of which are sharpened for engagement with the work. The forward portion of the cutting unit 7 is provided between the ends thereof with what might be said to be a cam groove 8, the inner wall of which extends at an angle to the plane of the cutting unit for engagement by the cam surface 9 of a locking and locating block 10. The cam surface 9 is formed by reducing the forward portion of the block 10 as illustrated in Figure 6.

In carrying out the invention the rectangular locking and locating block 10 is slidably and non-rotatably received in a squared opening or socket 12 in the body. The inner portion of the opening 12 intersects the forward portion of the transverse opening 6 so that the cam surface 9 may enter the groove 8 and have effective contact with the inner or bottom wall of the same whereby the rear edge of the cutting unit may be forced into effective contact with the rear wall of the bar.

As illustrated in Figure 6 the rear portion of the locking and locating block 10 is provided with a socket 14 to receive the head 15 of the locking screw 16. Particular attention is directed to the fact that the socket 14 is elongated in plan view and therefore freely receives the head 15 so that the head may be freely turned therein. The head 15 is, however, held within the socket 14 by a pair of retaining pins 17, the ends of which are anchored to the block 10 in such a manner that the intermediate portions of pins are positioned within the socket at opposite sides of the head 15 to engage the head. This provides a simple and reliable means to rotatably

connect the locking screw 16 to the block 10 and at the same time to permit the block 10 to partake of a limited lateral movement without in any way disturbing the connection 5 between the screw and the block.

Referring now to Figure 3, it will be seen that the locking screw 16 is carried by an internally and an externally threaded bushing 20 threaded into one side of the bar at 10 about 90 degrees to the plane of the slot 6.

Preparatory to positioning the block 10 and associated elements in their proper places for the use of the bar, the rear terminal portion of the locking screw is threaded into the inner 15 end of the bushing 20 and the block 10 is then positioned in the squared opening 12. After this, the bushing 20 is screwed into its socket in the bar, during which the screw 16 will be drawn into the bushing. The rear portion of 20 the locking screw may have a hexagonal socket for the reception of a portion of an Allen wrench or it may have any other tool engaging means found desirable.

After the cutting unit has been placed in 25 the slot 6 and engaged by the locking and locating block 10 the oppositely positioned locating screws 30 may be advanced into engagement with opposite sides of the block 10 as suggested in Figure 2. The screws 30 may 30 be turned in or out to adjust the cutting unit within the slot 6 to cause the cutters at opposite sides of the bar to perform equal work as will be obvious to those skilled in the art. After the cutting unit has been adjusted the 35 threaded openings which receive the screws 30 may be plugged with sealing wax or the like. In this connection it is noted that the rear portions of the locating screws 30 terminate a sufficient distance inwardly of the periphery of the bar to permit of the placing 40 of sealing wax. The exposed portion of the threads in the openings will act as an anchoring means for the wax.

It is believed to be obvious that during the 45 adjustment of the cutting unit 7 the sides of the block will be engaged with the more or less triangular end walls or shoulders 35 at the ends of the cam groove 8 whereby the turning of the screws 30 in the proper directions will result in the transverse adjustment of the cutting unit 7.

Particular attention is directed to Figure 4 which illustrates that the squared opening or socket 12 is sufficiently wider than the block 10 55 to provide for all reasonable adjustment of the cutting unit. In this connection it is also noted that the socket 14 is sufficiently longer than the lateral dimension of the head 15 to permit of lateral movement of the head 10 60 under the influence of the screws 30.

For subsequent adjustment of the locking unit 7, sealing wax previously referred to, may be removed to afford access to the grooves or other tool engaging means at the rear ends 65 of the screws 30.

With reference to the foregoing description taken in connection with the accompanying drawings it will be seen that the cutting unit may be expeditiously and securely locked in place without the aid of the taper locking 70 screw ordinarily employed. It will be further seen that the thrust on the cutters is transmitted directly to the rear wall of the slot 6 so that the tendency of the cutting unit to shift when once adjusted is substantially 75 reduced.

In use the cutting blocks can be taken to the tool room of a machine shop or other place of use and by placing them in a jig with a location lug engaging the cam groove 80 8 all blades may be set alike or substantially alike. However, if it is found when the cutting block is again placed in the boring bar that the cutting blades do not indicate at true with each cutting tool the error may be 85 corrected by adjustment of the screws 30 after which the screw holes are filled with melted wax. When this has been done all cutting tools can then be set to size in the tool room by tool machinists or makers and the tools 90 may be sent out into the shop for use by machine operators of limited intelligence. Therefore, the use of this invention permits manufacturers to secure accurate holes without being forced to employ highly skilled 95 machinists to use the tools.

Having thus described the invention, what is claimed is:

1. A boring bar comprising a body having removable cutting unit, receiving and sustaining means therefor, said body being provided with an opening extending substantially transversely of the cutting unit and communicating laterally therewith, a locking and locating block in said opening, a locking screw, the block and screw having means for effecting a rotatable connection between the same and permitting movement of the block lengthwise of the cutting unit, a bushing threaded into said body and through which said screw is threaded, and locating means to engage said block to move the same laterally.

2. A boring bar comprising a body having a slot and an opening communicating with the slot, a cutting unit in said slot and having a pair of shoulders, a locking and locating block adapted to extend between said shoulders and engage said unit to secure the same in place, one of the contiguous portions of the block and unit between said shoulders being bevelled transversely of the axis of the unit to define a cam, means whereby said block may be advanced and retracted, and permitting movement of the block in the direction of the length of the slot, and means engaged with said block to move the same and the cutting unit transversely of the body.

3. A boring bar comprising a body having a slot extending entirely therethrough and

having an opening communicating with the forward portion of the slot, a cutting unit in said slot and having a cam groove in the forward portion thereof and provided with a bottom wall extended at an angle to the plane of the cutting unit and having end walls, a locking and locating block in said opening and having a cam surface engaged with the bottom wall of said cam groove, a locking screw connected to said block, the block and screw having means whereby the two may be relatively adjusted in the direction of the length of the slot which is to say transversely of the opening, means engaged 15 with said block to adjust the same and said unit transversely, and the relative lengths of said opening and block being such as to assure a bearing engagement of the block in said slot when in its various operative positions.

4. A boring bar comprising a body having a slot and an opening, said opening being squared, a cutting unit in said slot and having a cam groove and end walls, a block of 25 rectangular formation in said squared opening and having a cam surface to extend into said cam groove and engage the end walls of the same, a locking screw rotatably connected to said block, said connection permitting transverse movement of the block 30 relatively of the screw, locating screws engaged with opposite sides of said block, and the relative lengths of said opening and block being such as to assure a bearing engagement of the block in said slot when in its various operative positions.

5. In a device of the class described, a body having a slot, a cutting unit therein, and the body being further provided with an opening extending substantially transversely of 40 said slot and communicating therewith at one side, the combination of a locking and locating block working in said opening, the block and cutting unit having interengaging 45 portions and the bottom of one of said portions being a cam surface, the block and cutting unit being thus connected for unitary movement in the direction of the length of the slot, the block having an elongated recess in its top surface and extending in the 50 direction of the length of said slot, a screw threaded into said body and having a constricted portion adjacent its inner end, said inner end of the screw being unthreaded and 55 being received in said recess of the block, pins removably carried by the block and extending lengthwise of the recess to confine the unthreaded screw end therein, and means for adjusting the cutting unit and block in 60 the direction of the length of the slot.

In testimony whereof I affix my signature.
FLOYD S. HARTWELL.
